(57) **CLAIM**

The ornamental design for a camera, as shown and described.

DESCRIPTION

FIG. 1 is a front, top, right perspective view of a camera showing our new design;

FIG. 2 is a front elevational view thereof;

FIG. 3 is a left side elevational view thereof; and,

FIG. 4 is a top plan view thereof.

The broken line drawing of the camera form no part of the claimed design. The dot-dash broken lines define the boundaries of, but not included in, the claimed design.
